United States Patent Office.

A. W. WHITE OF BOSTON, AND JOHN J. WATSON, OF GLOUCESTER, MASSACHUSETTS.

Letters Patent No. 96,174, dated October 26, 1869.

CHIN-REST FOR VIOLINS.

The Schedule referred to in these Letters Patent and making part of the same.

To all whom it may concern:

Be it known that we, A. W. WHITE, of Boston, in the county of Suffolk, and State of Massachusetts, and JOHN J. WATSON, of Gloucester, in the county of Essex, and State of Massachusetts, have invented a new and improved Chin-Rest for the Violin and Viola; and we do hereby declare that the following is a full and exact description thereof, reference being had to the accompanying drawings, and to the letters of reference marked thereon.

The nature of our invention consists in the method of fastening and tightening a chin-rest for the violin and viola.

Figure 1 represents a violin with our device attached.

Figure 2 is a view of the device by itself.

Figure 3 is a section of fig. 2, obtained by cutting it through in the centre, in the line *x y*, showing the method by which the screw is attached, &c.

In fig. 2, *a* is the portion of the rest lying on the upper side of the violin, being that portion upon which the chin of the performer rests. *b* is that portion pressing against the lower side of the violin. *e* is a screw, turned to the right or left by the handle *c*, which is fastened to the screw *e*. *d* and *f* (see fig. 3) are projections or shields, for the purpose of holding the screw *e* in place, and preventing it from slipping out of the upper part of the rest *a*. The lower part of the rest, *b*, runs up and down the screw *e*, at the pleasure of the performer.

In using our chin-rest, we first place it upon the violin or viola, as in fig. 1; then, by turning the

handle *c* to the left, tighten the rest by bringing the parts *a* and *b* closer together, pressing them against the upper and lower sides of the instrument respectively.

To loosen the rest, in order to remove it, we simply turn the handle *c* to the right, thus turning the screw *e* and widening the distance between the parts *a* and *b*.

We are aware that there are devices for this purpose already in the market, the one tightening by means of a spring being used, perhaps, more than any other. None, however, are now in general use.

We consider ours superior to all others, inasmuch as it can be made tighter than others, will not loosen, is easily tightened, is more convenient, and more durable, as the spring is very likely to get loose and lose its power.

We do not claim a violin-holder for the chin as anything new or novel.

We do not claim the parts *a* and *b*, in themselves, as our invention.

What we claim as our invention, is—

The combination and arrangement of the screw *e* with the handle *c* attached, combined and arranged with the holds or shields *d* and *f*, for the purpose of tightening and loosening a chin-rest for the violin and viola.

JOHN J. WATSON.
A. W. WHITE.
